UNITED STATES PATENT OFFICE.

ADAM MACHOROSKI, OF KEWANEE, ILLINOIS.

CAR-COUPING.

1,257,904.

Specification of Letters Patent. Patented Feb. 26, 1918.

Application filed October 15, 1917. Serial No. 196,681.

To all whom it may concern:

Be it known that I, ADAM MACHOROSKI, a citizen of the United States of America, residing at Kewanee, in the county of Henry 5 and State of Illinois, have invented certain new and useful Improvements in Car-Couplings, of which the following is a specification.

This invention relates to certain new and 10 useful improvements in car couplers.

The primary object of the invention is to provide a coupler for cars that is easy and cheap to manufacture but at the same time possesses great strength and is formed so as 15 to consume an exceedingly small amount of space upon the cars.

A further object is to provide a coupler for cars pivoted for operation within cut-away portions of the end platforms of the 20 car and furnished in pairs, one being carried at each end of each car, each pair being operable when adjacent cars are coupled together for releasing from opposite sides of the train.

25 A still further object is to provide a pivoted coupler and a keeper at each end of cars and means upon each car for releasing the engaged couplers when the adjacent cars are secured together thereby.

30 With these general objects in view and others that will appear as the nature of the invention is better understood, the same consists in the novel combination and arrangement of parts to be hereinafter more fully 35 described, illustrated in the accompanying drawings, and set forth in the appended claim.

In the drawings forming a part of this 40 application and in which like-designating characters refer to corresponding parts throughout the several views—

Figure 1 is a side elevation of portions of two cars provided with the present invention coupling the cars together, a portion of 45 one platform being shown broken away, and one of the couplers with its operating cam shown in dotted lines in its releasing position.

Fig. 2 is a top plan view thereof.

50 Fig. 3 is an end elevation of the car provided with the device.

Fig. 4 is a vertical transverse sectional view taken upon line IV—IV of Fig. 2, and

55 Fig. 5 is a perspective view of the coupler operating means detached.

Referring more in detail to the drawings,

the portions of two cars 10 and 11 are disclosed in the drawing provided with end platforms 12 and 13 respectively each provided with an identical form of coupling means. A coupler 14 is pivoted by means of its cylindrical head 15 within a vertical opening 16 of each end platform of each car, the same being mounted upon a pivot bar 17 traversing the said opening 16 and journaled in a bushing 18 carried by the platform. It will be noted from an inspection of Fig. 2 that the cylindrical head 15 is wider than the shank of the coupler 14 and that the vertical opening 16 is wider than 60 the slot which receives the shank. The purpose of this is to relieve the pull on the pivot bar 17 and bring a part of the stress directly on the platform. A cap 19 is provided at the outer end of the bushing and 65 at one side edge of the platform for closing the bushing end and retaining the rod 17 therein, the said plate being retained by means of suitable screws 20. The underside of the coupler being cut-away as at 21 allows the coupler to rest horizontally within 70 the slot 22 of the car platform and engaging the bottom 23 of the said slot.

The cutting away of the lower side of the coupler provides a forwardly positioned 85 hook 24 at the free end and upon the under side of the coupler which has its forward end 25 beveled or curved. Each platform is also provided with a keeper opening 26 vertically positioned therethrough and having 90 an entrance groove 27 for receiving the hooked end of the coupler when the cars and their platform are moved together, the groove having an inclined front bottom portion 28 up which the end of the coupler 95 is adapted to ride upon its curved surface 25 until the hook 24 rides over the forward edge of the keeper opening 26 and engages the inclined keeper edge 29 of the said opening.

100 Each platform is provided with a coupler releasing member formed of a shaft 30 revolvably journaled therebeneath in spaced brackets 31, the said shaft having at one of its outer ends a turning crank 31. These 105 cranks are preferably provided at only one end of each of the shafts 30 and at opposite sides of the car upon the opposite end platforms thereof, although it is obvious that the shafts may be of sufficient length to provide an operating crank at each end thereof.

110 The adjacent platforms 12 and 13 being

provided with similar couplers and keeper openings, it will be seen that a positioning of the cars together and with the adjacent ends of the platforms in substantial contact with each other, the couplers will automatically become engaged with the keeper faces 20 of the keeper openings and at which time the pair of couplers will firmly lock the cars together. The bottom of the grooves 27 are 10 provided with notches 32 while the bottom 23 of the coupler-receiving groove 22 are provided with similar notches 33 and whereby similar cams 34 fixed to and carried in spaced relation upon the shaft 30 are 15 adapted to move upon operative turning of the shaft crank 31. It will thus be seen that when the pair of couplers are in engagement as shown in Fig. 2 for coupling the cars together, the two couplers may be readily 20 opened by one of the cranks 31 which are positioned at opposite sides of the cars, a turning of either crank effecting an upward movement of its cams 34 through the notches 32 and 33 and thus engaging the 25 lower side of each of the pair of couplers and elevating each of the same and disengaging the hooks 24 from the keeper faces 29.

The shaft 30 is secured within the brackets 31 by means of exteriorly positioned collars 35 secured to the shaft. It will thus be seen that a coupler is provided composed of two parts and of simple construction but which

will automatically couple the cars together in firm engagement while readily releasably 35 manually from either side of the train.

While the forms of the invention herein shown and described are what are believed to be the preferred embodiments thereof, it is nevertheless to be understood that minor 40 changes may be made without departing from the spirit and scope of the invention as claimed.

What I claim as new is:—

The combination with two opposed car 45 platforms, the first of said car platforms having pivoted thereto for vertical movement, a coupler having its free end provided with a hook, the second of said car platforms having means to engage said hook, a 50 shaft extending transversely of the second platform beneath the said hook, an ovate cam fixed at its smaller end on said shaft beneath said hook, and constituting a weight to normally hold the shaft in a fixed position and present an enlarged continuously curved cam face, and a handle on said shaft of less weight than the cam whereby the cam normally rests in depending position, 55 said cam being arranged when the handle is manually rotated to engage the hook and disengage the latter from the hook retaining means.

In testimony whereof I affix my signature,

ADAM MACHOROSKI.
